DESIGN FOR A DRESS ENSEMBLE

Marie Mascitelli, New York, N. Y.

Application November 17, 1938, Serial No. 81,155

Term of patent 3½ years

To all whom it may concern:

Be it known that I, Marie Mascitelli, a citizen of the United States of America, residing in New York city, in the borough of Manhattan, county and State of New York, have invented a new, original, and ornamental Design for a Dress Ensemble, of which the following is a specification, reference being had to the accompanying drawing, forming part thereof, wherein

I claim:

The ornamental design for a dress ensemble, substantially as shown.

MARIE MASCITELLI.
